CLAIM

The ornamental design for a sandal, as shown and described.

DESCRIPTION

FIG. 1 is a frontal perspective view of a sandal showing my new design;

FIG. 2 is a top plan view of my new design;

FIG. 3 is a left side view of my new design;

FIG. 4 is a right side view of my new design;

FIG. 5 is a front view of my new design; and,

FIG. 6 is a rear view of my new design.

The surfaces of the sandal that are not shown form no part of the claimed design.
